UNITED STATES PATENT OFFICE.

ROBERT SAFFORD TOWNE, OF NEW YORK, N. Y., AND FREDERICK B. FLINN, OF ORANGE, NEW JERSEY, ASSIGNEES, BY MESNE ASSIGNMENTS, TO PNEUMATIC PROCESS FLOTATION COMPANY, OF NEW YORK, N. Y., A CORPORATION OF DELAWARE.

APPARATUS FOR SEPARATING ORE MATERIALS FROM EACH OTHER.

1,317,244.

Specification of Letters Patent.

Patented Sept. 30, 1919.

Application filed September 12, 1914. Serial No. 861,435.

To all whom it may concern:

Be it known that we, ROBERT S. TOWNE and FREDERICK B. FLINN, citizens of the United States, residing at New York and Orange, in the counties of New York and Essex and States of New York and New Jersey, respectively, have invented certain new and useful Improvements in Apparatus for Separating Ore Materials from each other, of which the following is a specification, reference being had therein to the accompanying drawing.

The invention relates to an apparatus for treating ores for the purpose of separating the metalliferous particles from the non-metalliferous particles thereof; and it relates particularly to an apparatus in which the separation is effected by means of relatively large bubbles of air which are caused 20 to pass upward through a liquid pulp of the ore and withdraw the metalliferous particles therefrom.

The principal object of the invention is to provide means whereby the ore can be successively introduced into two or more receptacles considerably above the bottoms thereof and in each of them subjected to the action of air bubbles to effect removal of the metalliferous particles. Another object of 30 the invention is to provide a separating apparatus having an improved ore holding receptacle, improved ore feeding devices and improved bubble receiving devices. Other objects will be apparent from the following 35 specification and claims.

Of the drawings,

Figure 1 is a vertical sectional view showing one embodiment of the invention.

Fig. 2 is a plan view of the construction 40 shown in Fig. 1.

Fig. 3 is an end view of the construction shown in Fig. 1.

Fig. 4 is a vertical sectional view similar 45 to Fig. 1 but showing a modified form of apparatus.

Fig. 5 is a plan view of the apparatus shown in Fig. 4.

Fig. 6 is an end view of the apparatus shown in Fig. 4.

50 Referring to the drawings, especially Figs. 1, 2 and 3, 1 and 2 represent, respectively, two tanks or receptacles in which the ore is contained while being treated. These re-

ceptacles are shown as constructed of sheet metal, but it will be understood that other materials may be used when desired. The receptacles are also shown as being rectangular in horizontal cross section but, as to the shape, there can be wide variation. However, the rectangular shape shown has many features of advantage and when it is used, we prefer to provide the two receptacles with a common division wall such as that indicated at 3. The receptacle 2 is much deeper than the receptacle 1, the bottom of the receptacle 1 being well above that of the receptacle 2. Above the true bottoms of each of the receptacles there are provided false bottoms 4 and 5 which are formed of some suitable porous material such as silica sponge, carborundum, a plurality of perforated metal plates, sheets of canvas, etc. The porous bottom 4 of the receptacle 1 is inclined downward toward the partition 3 and the partition is provided with an opening 6 just above the said bottom. The porous bottom 5 in the receptacle 2 is similarly inclined toward an aperture 7 in the wall of the receptacle. The two apertures 6 and 7 extend horizontally entirely across the receptacles, and vertically adjustable gates 8 and 9 are provided for opening and closing them and regulating the flow of material therethrough.

The aperture 7 communicates with a discharge chamber 10 which preferably has two bottom sections inclined oppositely to discharge openings 11, 11. Communicating with the discharge openings 11, 11, are pipes 12, 12, controlled by valves 13, 13. Connected with the pipes 12, 12 above the valves are supplemental discharge pipes 14, 14, which preferably are formed of flexible hose.

Valved air pipes 15 and 16 communicate respectively with the spaces below the two porous bottoms 4 and 5. These air pipes are connected with a suitable source of compressed air and, by means of them, air pressures can be maintained in the said spaces, the result being that air is forced upward through the said porous bottoms and into the receptacles to form relatively large uniformly distributed bubbles therein.

The ore pulp to be treated is fed initially into the receptacle 1. The feeding can be effected in any of a number of ways, but we

2
 prefer devices such as those shown. 17 is an initial pulp receiver mounted centrally above the receptacle 1. Ore is supplied to it in a stream by means of a trough 18. A plurality of pipes 19, 19 extend downward from the receiver 17 and into the receptacle 1. These pipes are open at their lower ends and immediately below their lower ends there are positioned distributing devices 20, 20. These distributing devices are supported by rods 21 which extend upward through the pipes and are supported at their upper ends by means of thumb screws 22 on brackets 23. By adjusting the thumb screws 24 the rods and distributing devices can be raised or lowered and the rate of flow through the pipes can be varied. The distributing devices serve to throw the ore outward and distribute it in a substantially horizontal sheet over the entire cross sectional area of the receptacle.

The ore introduced in the way above described is permitted to flow through the opening 6 into the receptacle 2 and to accumulate in the two receptacles to suitable levels.

These levels can be maintained and controlled by means of the devices which have been shown and described. The level in the receptacle 1 can be controlled either by regulating the rate of feed or by regulating the rate of discharge by changing the position of the gate 8; and the level in the receptacle 2 can be regulated either by changing the position of the gate 9 or by regulating the valves 13, 13, or, when the pipes 14, 14 are used, by raising or lowering their outer discharge ends.

The partition wall 3 between the two receptacles and the end walls of the receptacles are carried upward above the outer side walls. Arranged along these outer side walls are bubble receivers 24 and 25, the bottoms of these receivers preferably being inclined oppositely from the center.

In using the apparatus embodying our invention, the ore, after being first pulverized, (when pulverization is necessary) is formed into a suitable liquid pulp, and oil, when necessary may be a constituent. This pulp is introduced in a stream into the initial receiver 17 from which it flows downward through the pipes 19, 19 into the receptacle 1, the devices 20 serving as aforesaid to distribute the ore substantially uniformly over the entire cross sectional area of the receptacle. At the same time, air is permitted to flow through the pipe 15 into the space beneath the porous bottom 4. The air forces its way through the porous bottom and into the body of pulp in the receptacle in the form of relatively large air bubbles which are uniformly distributed horizontally and which rise in rapid succession to substantially fill the entire volume. This mass of

vertically rising bubbles engages the downward moving ore pulp and the bubbles having an affinity for the metalliferous particles (which may be oiled when necessary), collect these particles in their films and carry them upward, the non-metalliferous particles being permitted to continue downward. The bubbles carrying the metalliferous particles in their films continue to move upward above the top of the pulp and the successively emerging bubbles are carried upward by those that follow, with the result that there is formed a bubble column extending to the top of the receptacle. The metalliferous particles are retained by the bubbles in the said column but the said bubbles have little or no ability to carry non-metalliferous particles and the result is that any non-metalliferous particles that may have reached the surface of the pulp are dropped a short distance above the surface. The bubbles which reach the top of the column are well laden with metalliferous particles but are substantially free from non-metalliferous particles. At the top of the receptacle the upper part of the bubble column carrying only metalliferous particles is separated from the lower part which may contain some non-metalliferous particles. This separation is effected by gravity, the upper bubbles being permitted to flow over the side wall of the receptacle and into the receiver 24. In this receiver some of the bubbles may break down but those which remain, together with the liquid resulting from those which burst, flow along the inclined bottom of the receiver to be discharged and conducted to a suitable place for further treatment.

With an apparatus such as that contained in the receptacle 1, it is found that under some conditions, especially when the rate of pulp flow is high, the separation of the metalliferous particles is not entirely complete. In order to save any metalliferous particles in the residue discharged from the first receptacle, the second receptacle 2 is provided. The residue from the receptacle 1 is discharged into the receptacle 2 at points considerably above the bottom thereof and is distributed more or less uniformly over the cross sectional area thereof. Here again it is acted upon by bubbles formed at the plate 5 and the action is similar to that already described in connection with the receptacle 1. The bubbles carrying the metalliferous particles are discharged into the receiver 25 from which they can be led away for further treatment.

It will be understood that the actions in the two receptacles 1 and 2 can be varied independently of each other. The air pressures beneath the two plates 4 and 5 can be regulated so as to give each receptacle the most efficient rate of air flow, and, by means of the gates and valves, the depths of the

pulp in the two receptacles can be varied so as to give the most efficient results.

In Figs. 4, 5 and 6 we have shown a modification of the apparatus in which not only two receptacles are provided, but three. The receptacles 1^a and 2^a are similar to those already described. The receptacle 26 is similar to receptacle 2^a but is deeper. It is arranged to receive the pulp through the 10 discharge aperture 7^a. The ore from the receptacle 26 is discharged through an aperture 27 into a discharge chamber 28 which is similar to the discharge chamber 10 before referred to. This discharge chamber 16 28 can, if desired, have its walls continued upward as shown instead of being closed at the top as in the discharge chamber 10 in the other mechanism. The aperture 27 is controlled by an adjustable gate 29. The 20 receptacle 26 has a porous plate 30 in the bottom similar to those already described and similarly connected with the source of air supply.

The bubbles from the two receptacles 2^a and 26, instead of being discharged at the sides, are discharged at the ends into the receivers 31 and 32.

The operation of the apparatus shown in Figs. 4, 5 and 6 is similar to that of the apparatus shown in Figs. 1, 2 and 3, and a further specific description thereof will not be necessary.

It is sufficient to point out that this apparatus provides for a still further refinement of process. It provides for a third treatment of the ore initially introduced into the receptacle 1.

What we claim is:

1. In an apparatus for separating the metalliferous from the non-metalliferous ingredients of an ore mass, the combination of a plurality of closely adjoining pulp receptacles; porous media in the lower parts of the receptacles respectively; means for supplying air under pressure below the said porous media and forcing it therethrough to form air bubbles substantially uniformly distributed across the receptacles; means for supplying ore pulp to the first receptacle, 40 said pulp being acted upon by the bubbles in the said receptacle to remove the metalliferous ingredients therefrom; means for removing the metal-laden bubbles from each receptacle at points above the surface of the 45 pulp body, said air supplying means being spaced from each other and having progressively increased spacing from the bubble overflow; means for discharging pulp from the first receptacle near the bottom thereof 50 and directly feeding it to the next receptacle at the side thereof and above the porous media therein, the air being further acted upon by the bubbles in the next receptacle to remove additional metalliferous ingredients therefrom; and means for discharging 55

the pulp from said next receptacle at the side opposite to the point of feeding.

2. In an apparatus for separating the metalliferous from the non-metalliferous ingredients of an ore mass, the combination of 70 a series of closely adjoining pulp receptacles; porous gas distributors in the lower parts of the receptacles respectively; means for supplying gas under pressure below the said distributors and forcing it therethrough 75 to form gas bubbles substantially uniformly distributed across the receptacles; means for supplying ore pulp to the first receptacle of the series at a point above the gas distributor therein, the said pulp being acted 80 upon by the bubbles in the first receptacle to remove metalliferous ingredients therefrom; regulable means for discharging the pulp from the first receptacle directly to the second receptacle at a point above the porous gas distributor therein where it is acted 85 upon by the bubbles in the second receptacle to remove additional metalliferous ingredients from the pulp; means for discharging the pulp from the second receptacle; and 90 means for removing the metal-laden bubbles from each receptacle at a point above the surface of the pulp body, said porous gas distributors being spaced from each other and having progressively increased spacing 95 from the bubble overflow.

3. In apparatus for separating the metalliferous from the non-metalliferous ingredients of an ore mass, the combination of a plurality of closely adjoining pulp receptacles; porous gas distributors in the lower parts of the receptacles respectively, one of the porous gas distributors being higher than the other; means for supplying a gaseous medium under pressure into said distributors and forcing it through the porous surface thereof to form bubbles substantially uniformly distributed across the receptacles; means for supplying the ore pulp to the receptacle having the higher gas distributor above said distributor, the said pulp being acted upon by the bubbles in the said receptacle to remove the metalliferous ingredients therefrom; means for the direct gravity discharge of the pulp from a point 100 immediately above the gas distributor in the first receptacle to a point above the gas distributor in the next receptacle, the ore being further acted upon by the bubbles in said next receptacle to remove additional metalliferous ingredients therefrom; means for discharging the pulp from the second receptacle; and means for removing the metal-laden bubbles from each receptacle at a point above the surface of the pulp body, 115 said gas distributors being spaced from each other and having progressively increased spacing from the bubble overflow of the receptacle.

4. In an apparatus for separating the metal-

- 4
- liferous from the non-metalliferous ingredients of an ore mass, the combination of a plurality of directly connecting pulp receptacles arranged closely adjacent each other 5 with a common division wall having an aperture near the bottom of one and above the bottom of the other, porous plates in the lower parts of the receptacles respectively, the plate in a receptacle being immediately below the said aperture and the plate 10 in the succeeding receptacle being considerably below the aperture, means for supplying air under pressure below the said porous plates and forcing it therethrough to form relatively large air bubbles substantially uniformly distributed across the receptacles, 15 means for supplying ore pulp to the first receptacle at points above the porous plate therein, the said pulp being acted upon by the bubbles in the said first receptacle to remove metalliferous ingredients therefrom and then flowing through the said aperture into the next receptacle where it is acted upon by the bubbles therein to remove further metalliferous ingredients therefrom, 20 means for discharging the pulp from the last receptacle, and means for removing the metal-laden bubbles from each receptacle at points above the surface of the pulp body.
- 30 5. In an apparatus for separating the metalliferous from the non-metalliferous ingredients of an ore mass, the combination of a container for a body of ore pulp, a vertical partition dividing the container into sections, porous plates in the lower parts of the sections respectively, means for supplying air under pressure below the said porous plates and forcing it therethrough to form relatively large air bubbles substantially uniformly distributed across the sections, 35 means for supplying ore pulp to the container at points above the porous plates therein, the said pulp being acted upon by the bubbles in the container to remove metalliferous ingredients therefrom, means for discharging the pulp from the two sections, 40 means for regulating the flow of pulp through the two sections to maintain the pulp level in one of them different from that in the other, and means for removing the metal-laden bubbles from each receptacle at a point above the surface of the pulp body, 45 said porous plates being spaced from each other and having progressively increased spacing from the bubble overflow.
- 55 6. In an apparatus for separating the metalliferous from the non-metalliferous ingredients of an ore mass, the combination of a container for a body of ore pulp, a vertical partition dividing the container into sections, porous plates in the lower parts of the sections respectively, means for supplying air under pressure below the said porous plates and forcing it therethrough to form relatively large air bubbles substantially uni-
- formly distributed across the sections, means for supplying ore pulp to the container at points above the porous plates therein, the said pulp being acted upon by the bubbles in the container to remove metalliferous ingredients therefrom, means for discharging the pulp from the two sections, and bubble receivers for the two receptacles respectively arranged on opposite sides of the said partition, said porous plates being spaced from each other and having progressively increased spacing from the bubble overflow. 70
7. In an apparatus for separating the metalliferous from the non-metalliferous ingredients of an ore mass, the combination of a pulp receptacle, said receptacle being divided into compartments which directly communicate through a transverse substantially constricted passage; a porous medium in the lower portion of each compartment of the receptacle, the porous mediums of successive compartments being arranged in stepped relation, each of said porous mediums forming a separate and independent gas-diffusing unit, means supplying a gaseous medium under pressure below the said porous mediums and forcing it therethrough to form uniformly distributed air bubbles; means for supplying ore pulp to the receptacle, the said pulp being acted upon by the said bubbles to remove the metalliferous ingredients therefrom; and means for collecting and discharging from the receptacle the resulting barren pulp. 80
8. In an apparatus for separating the metalliferous from the non-metalliferous ingredients of an ore mass, the combination of a pulp receptacle, a porous plate in the lower part of the receptacle, means for supplying air under pressure below the said porous plate and forcing it therethrough to form relatively large substantially uniformly distributed air bubbles, a plurality of horizontally acting spray devices arranged in a series longitudinally of the receptacle for supplying ore pulp to the receptacle at a plurality of points remote from the sides thereof, the said pulp being acted upon by the said bubbles to remove the metalliferous ingredients therefrom, and means for collecting and discharging from the receptacle the resulting barren pulp. 90
9. In a frothing classifier, a tank and means for admitting air to said tank, said means comprising a series of air chambers disposed at different levels in stepped arrangement and means for supplying air to the several chambers at different pressures, respectively. 105
10. In a frothing classifier, a compartment tank and means for admitting a gaseous medium thereto, said means comprising a series of separated gas distributers in stepped relation at the bottom of the tank compartments and discharging upwardly into the tank, each of said distributers serv- 110
- 115
- 120
- 125
- 130

ing to direct pulp to a succeeding lower distributor, and means for supplying gas to the several distributors.

11. A frothing classifier, comprising a tank having a plurality of closely adjoining compartments, each of said compartments having an independent gas-distributing unit in its lower part, and pulp feeding means leading from the bottom of one compartment and directly connecting with the next adjacent compartment above the gas distributing unit thereof, said units being in stepped relation, each of said units serving, also, to direct pulp to a succeeding lower unit.

12. A frothing classifier comprising a tank having a plurality of closely adjoining compartments each provided with separate and independent means for admitting a gaseous medium thereto at the lower part thereof, said means being in stepped relation, and pulp-feeding means in a wall separating adjacent tanks or compartments and leading from the bottom of one tank or compartment to the next adjacent tank or compartment above the gas admitting means thereof.

13. A frothing classifier comprising a tank having a plurality of closely adjoining compartments each provided with separate and independent means for admitting a gaseous medium thereto at the lower part thereof, said means being in stepped relation, pulp-feeding means in a wall separating adjacent tanks or compartments and leading from the bottom of one tank or compartment to the next adjacent tank or compartment above the gas admitting means thereof, a central feed pipe leading into the first compartment, and a launder at the top of the classifier for overflow bubbles.

14. A flotation tank having a bubble overflow in an upper portion, said tank increasing in depth from a pulp feed portion toward a pulp discharge portion, means forming the tank into successive communicating compartments, and separate means in the bottom of each compartment for distributing a gaseous medium thereinto substantially throughout the cross area of the contents of the compartment, said means being in stepped relation, the gas distributing means for the compartment being independent and having progressively increased spacing from the bubble overflow at the upper portion of the tank.

15. A flotation tank adapted to contain a deep body of powdered ore, water and a frothing agent, said tank increasing in depth from one portion to another, means dividing the interior of the tank into communicating compartments, independent gas distributors in the bottom of the compartments arranged at different levels and each having a porous surface adapted to deliver fine streams of gas upwardly throughout substantially the cross area of the pulp contents thereabove,

to produce pneumatic flotation of the metalliferous particles of the ore mass, said surfaces being arranged in stepped relation, means for admitting a gaseous medium to said distributor, and means for removing 70 the metal-laden bubbles from the tank above the liquid level thereof.

16. A flotation tank adapted to contain a deep body of powdered ore, water and a frothing agent, means dividing the interior 75 of the tank into communicating compartments, independent gas distributors in the bottom of the compartments and each having a porous surface adapted to deliver fine streams of gas upwardly throughout substantially the cross area of the pulp contents thereabove, to produce pneumatic flotation of the metalliferous particles of the ore mass, said distributors being arranged in stepped relation, the points of communication between succeeding compartments of the tank being proximate the porous surface of the gas distributors of a preceding compartment, means for admitting a gaseous medium to said distributors, and means for 90 removing metal-laden bubbles from the tank above the liquid level thereof.

17. A flotation tank adapted to contain a deep body of powdered ore, water and a frothing agent, and having a partition dividing the interior of the tank into compartments, said compartments communicating through a restricted passage below the partition; independent gas receivers in the compartments of the tank having porous upper surfaces for discharging fine streams of gas into the fluid contents of the compartments to produce pneumatic flotation of the mineral constituents of the ore mass, said gas receivers being arranged in stepped relation 100 and each being separate from the others, means for supplying a gaseous medium to said receivers, and means for discharging tailings from the tank, said tank having a bubble overflow at the upper portion.

18. A flotation tank adapted to contain powdered ore, water and a frothing agent, said tank having a plurality of successive separated gas receiving chambers in its bottom, said chambers each having a porous upper surface through which the gaseous medium is emitted into the fluid contents of the tank to produce pneumatic flotation of the metalliferous constituents of the ore mass and being relatively arranged in stepped relation, and means for introducing a gaseous medium into said separated receivers.

19. An apparatus for separating metalliferous from non-metalliferous particles of an ore mass comprising a plurality of chambers, the bottoms of said chambers being progressively stepped, means to emit gas bubbles in each of said chambers in proximity to the bottom thereof, and means to 125 130 135 140 145 150 155 160 165 170 175 180 185 190 195 200

permit flow of tailings from one chamber adjacent the bottom thereof to the adjacent chamber, whereby said tailings will be subjected to concentration by said gas bubbles 5 in said second chamber.

20. An apparatus for separating metalliferous from non-metalliferous particles of an ore mass comprising a plurality of chambers, the bottoms of said chambers being progressively stepped, means to emit gas bubbles in each of said chambers in proximity to the bottom thereof, means to permit flow of tailings from one chamber adjacent the bottom thereof to the adjacent chamber, 10 whereby said tailings will be subjected to concentration by said gas bubbles in said second chamber, and a discharge receptacle in communication with the last of said chambers in the direction of progression of the tailings. 15

21. An apparatus for separating metalliferous from non-metalliferous particles of

an ore mass comprising a plurality of chambers, the bottoms of said chambers being progressively stepped, means to emit gas bubbles in each of said chambers, in proximity to the bottom thereof, means to permit flow of tailings from one chamber adjacent the bottom thereof to the adjacent chamber, whereby said tailings will be subjected to concentration by said gas bubbles in said second chamber, and a discharge receptacle 25 in communication with the last of said chambers in the direction of progression of the tailings, the bottom of said receptacle 30 being below the discharge zone of said last named chamber. 35

In testimony whereof, we affix our signatures, in presence of two witnesses:

ROBERT SAFFORD TOWNE.
FREDERICK B. FLINN.

Witnesses:

DAVID SCOTT,
R. E. SAFFORD.

It is hereby certified that in Letters Patent No. 1,317,244, granted September 30, 1919, upon the application of Robert Safford Towne, of New York, N. Y., and Frederick B. Flinn, of Orange, New Jersey, for an improvement in "Apparatus for Separating Ore Materials from Each Other," an error appears in the printed specification requiring correction as follows: Page 3, line 62, claim 1, for the word "air" read *ore*; and that the said Letters Patent should be read with this correction therein that the same may conform to the record of the case in the Patent Office.

Signed and sealed this 18th day of November, A. D., 1919.

[SEAL.]

M. H. COULSTON,

Acting Commissioner of Patents.

Cl. 83—85.
